US00D855044S

(12) **United States Design Patent** (10) Patent No.: **US D855,044 S**
Cho et al. (45) Date of Patent: ** Jul. 30, 2019

(54) **MOBILE PHONE**(71) Applicant: **Samsung Electronics Co., Ltd.**, Suwon-si (KR)(72) Inventors: **Youngjun Cho**, Suwon-si (KR); **Sanghoon Song**, Gumi-si (KR); **Junyoung Lee**, Seoul (KR); **Munhee Jang**, Yongin-si (KR); **Youn-Gun Jung**, Suwon-si (KR); **Yoonyoung Choi**, Seoul (KR)(73) Assignee: **SAMSUNG ELECTRONICS CO., LTD.**, Suwon-si (KR)(**) Term: **15 Years**(21) Appl. No.: **29/685,297**(22) Filed: **Mar. 27, 2019****Related U.S. Application Data**

(63) Continuation of application No. 29/630,772, filed on Dec. 22, 2017.

(30) Foreign Application Priority Data

Jun. 23, 2017 (KR) 30-2017-0028975

(51) LOC (11) Cl. **14-03**

(52) U.S. Cl.

USPC ..... **D14/248****(58) Field of Classification Search**

USPC ..... D14/138 G, 138 AD, 341, 138 R, 496, D14/203.1, 203.3, 203.5, 203.7, 248, 439; 455/575.1, 556.2; D21/517, 329;

(57) CLAIM

The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the drawings depict portions of the mobile phone that form no part of the claimed design.

FIG. 1

FIG. 2

FIG. 3

FIG. 4

FIG. 5

FIG. 6

FIG. 7

FIG. 8
